Primary Examiner—Dominic Simone

[57] CLAIM

The ornamental design for a toy fan mobile, as shown.

DESCRIPTION

FIG. 1 is a perspective view;
FIG. 2 is a side elevational view;
FIG. 3 is a top plan view;
FIG. 4 is a bottom plan view; and,
FIG. 5 is a perspective view of a 5 blade version of my design.
The broken lines showing mobile support in FIGS. 1 and 5 is for illustrative purpose only and forms no apart of claimed design.
